[57] CLAIM

The ornamental design for a tobacco-impregnated toothpick, as shown and described.

DESCRIPTION

FIG. 1 is a perspective view of the tobacco-impregnated toothpick embodying the design of the present invention;

FIG. 2 is a front elevational view thereof, the rear being a mirror image of the front shown in FIG. 2;

FIG. 3 is a side elevational view thereof;

FIG. 4 is a side elevational view thereof;

FIG. 5 is a top plan view thereof; and,

FIG. 6 is a bottom view thereof.

FIG. 1.

FIG. 2.

FIG. 3.

FIG. 4.

FIG. 5.

FIG. 6.
